UNITED STATES PATENT OFFICE.

ROYAL A. CREW, OF PORTLAND, OREGON.

TEMPERATURE-REGULATOR.

1,107,761.

Specification of Letters Patent. Patented Aug. 18, 1914.

Application filed June 23, 1913. Serial No. 775,371.

To all whom it may concern:

Be it known that I, ROYAL A. CREW, a citizen of the United States, residing at Portland, in the county of Multnomah and 5 State of Oregon, have invented certain new and useful Improvements in Temperature-Regulators; and I do hereby declare the following to be a full, clear, and exact description of the invention, such as will enable 10 others skilled in the art to which it appertains to make and use the same.

This invention comprehends improvements in temperature regulators and relates more particularly to those which are adapted 15 to control a valve or damper.

One of the objects of the invention is to provide a temperature regulator including a receptacle for the expansive liquid, a barrel or cylinder in communication with said receptacle, a piston or plunger movable through the barrel, and a pivoted lever actuated by the movement of the piston or plunger, said lever being connected to the valve or damper.

25 The invention also contemplates the provision of an extremely strong and simple device of this nature which is especially adapted for use in connection with ice making machines to control the expansion valve.

30 With these and other objects in view, as will become more apparent as the description proceeds, the invention consists in certain novel features of construction, combination, and arrangement of parts, as will be 35 hereinafter described and claimed.

For a complete understanding of my invention, reference is to be had to the following description and accompanying drawings, in which,

40 Figure 1 is a vertical sectional view, partly in elevation, showing the regulator connected to a valve, Fig. 2 is a front elevation of the regulator, Fig. 3 is a top plan view, showing the device connected to a pipe, Fig. 45 4 is a side elevation, showing the regulator connected to a pipe, Fig. 5 is a detail sectional view showing a portion of the cylinder, guides, and piston, Fig. 6 is a sectional view taken on the plane of line 6—6 of 50 Fig. 1, and, Fig. 7 is a similar view taken on the plane of line 7—7 of Fig. 1.

In the preferred embodiment of my invention I provide a receptacle 10 which may be of any desired shape or construction, but 55 which is preferably made as shown in the

drawings, wherein it will be seen that it is somewhat cylindrically shaped and having an arcuate recess 11 formed in its flattened rear wall. The bottom 12 of the receptacle is a separate piece and is provided with an 60 opening 13 into which is threaded an adjusting plug 14. A barrel or cylinder 15 is integrally formed upon the top 16 of the receptacle and is longitudinally slotted upon opposite sides adjacent its upper end to form 65 the guides 17 and 18. Apertured lugs 19 are formed upon the upper extremities of the guides for the purpose of receiving fastening bolts. A plunger 20 which is slightly longer than the barrel is reciprocally mounted 70 therein and is connected by a rod 21 to a cross head 22 which slides between the guides 17 and 18. In order to prevent any of the expansive liquid leaking past the plunger 20, I counter-bore the upper end of the barrel, 75 as indicated by the numeral 23, and insert the packing rings 24. These rings are held in place by a packing gland 25 which is secured upon the rods 26 by means of the nuts 27. The gland extends into a counter-bore 80 and also projects beyond the guides so that it may be readily connected to the threaded rods at 26. If it is desired, a piston may be used in place of the plunger 20 and then the stuffing box may be dispensed with. 85

A supporting arm 28 is integrally formed with the guide 18 and extends outwardly and upwardly therefrom. A cross arm 29 is pivotally connected intermediate its ends to the extremity of the arm 28 and is provided with a laterally extending lever 30 which is formed with a longitudinal slot 31. A connecting rod 32 is secured at its lower end to the cross head 22 and at its upper end to the lever 30 by means of the bolt 33. A 90 plurality of weights 34 are suspended from the free extremity of the lever 30 for the purpose of drawing the same downwardly when the piston is lowered. In some cases it will be found more advantageous to employ a contractile spring in place of the weights. 95

In the drawings I have shown an expansion valve 35, such as is used in an ice making machine, operated by my temperature 100 regulator through the medium of the connections 36. When the valve 35 has been manually adjusted to about the right position it is connected to the cross bar 29. A fine adjustment may then be made by 110

threading the plug 14 inwardly or outwardly. Any increase in temperature will expand the mercury or alcohol within the receptacle 10 and force the plunger upwardly, causing the cross arm 29 to increase the opening of the expansion valve. Should the temperature decrease, the mercury or alcohol will contract and the weights 34 will cause the cross bar 29 to be turned so as to decrease the opening of the expansion valve. The longitudinal slot 31 makes it possible to shift the point of connection between the connecting rod 32 and lever 30 so as to vary the degree of movement of the latter with respect to the movement of the connecting rod.

From the foregoing description taken in connection with the accompanying drawings, it will be apparent that I have provided an extremely simple, durable, and practical temperature regulator, which may be used for various purposes.

It is to be understood that while I have shown and described the preferred embodiment of my invention, I do not wish to be limited to this exact construction, combination, and arrangement of parts, but may make such changes as will fall within the

spirit and scope of the invention as defined by the appended claim.

Having thus described my invention, what I claim is:

In a device of the character described, a liquid receptacle, an adjusting plug threaded therein, a barrel opening into the receptacle, guides forming continuations of the barrel, a supporting arm formed integrally with one of the guides, a cross bar pivoted intermediate its ends to said supporting arm, a lever extending at right angles from the intermediate point of the cross bar, said lever being provided with a longitudinal slot, a plunger movable within the barrel, a cross head, a connecting rod secured at one end to the cross head and at the other end to said lever, the point of connection with the lever being movable along the slot, and weights to draw the lever downwardly as the liquid contracts.

In testimony whereof I affix my signature in presence of two witnesses:

ROYAL A. CREW.
